(57) **CLAIM**

The ornamental design for a charge connector as shown and described.

DESCRIPTION

FIG. 1 is a front elevational view of a charge connector in an interlock release state showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top, and right side perspective view thereof;

FIG. 8 is a rear, bottom, and left side perspective view thereof;

FIG. 9 is a front, right, and bottom side perspective view thereof;

FIG. 10 is a rear, left, and top side perspective view thereof;

FIG. 11 is a front elevational view of a charge connector in an alternate position showing our new design;

FIG. 12 is a rear elevational view thereof;

FIG. 13 is a right side elevational view thereof;

FIG. 14 is a left side elevational view thereof;

FIG. 15 is a top plan view thereof;

FIG. 16 is a bottom plan view thereof;

FIG. 17 is a front, top, and right side perspective view thereof;
